UNITED STATES PATENT OFFICE

158,602

CLOCK

Adolph J. Nelson, Oak Park, Ill.

Application December 13, 1949, Serial No. 6,580

Term of patent 7 years

(Cl. D42—7)

To all whom it may concern:

Be it known that I, Adolph J. Nelson, a citizen of the United States of America, residing at Oak Park, Illinois, have invented a new, original, and ornamental Design for Clock, of which the following is a specification, reference being made to the accompanying drawing, forming part hereof.

Referring to the drawing, Fig. 1 is a front elevational view of a clock embodying my new design; Fig. 2 is a side elevational view and Fig. 3 is a top plan view of the same.

I claim:

The ornamental design for a clock, substantially as shown.

ADOLPH J. NELSON.
